UNITED STATES PATENT OFFICE.

WILLIAM C. McMURRAY, OF WELLSVILLE, OHIO.

ELECTRIC TRANSPORTATION SYSTEM.

No. 850,173.

Specification of Letters Patent

Patented April 16, 1907.

Application filed November 20, 1905. Serial No. 288,219.

To all whom it may concern:

Be it known that I, WILLIAM C. McMURRAY, a citizen of the United States of America, residing at Wellsville, in the county of Columbiana and State of Ohio, have invented certain new and useful Improvements in Electric Transportation Systems; and I hereby declare the following to be a full, clear, and exact description of the invention, such as will enable others skilled in the art to which it pertains to make and use the same.

This invention relates to improvements in electric transportation systems in which the cars are supported by the wires which carry the current for the motors which propel the cars.

The object of this invention is to provide a system of this character especially adapted for transporting general merchandise and market produce.

A further object of this invention is to simplify the construction of systems of this character and to provide means for securing economy in the use of the electric current.

My invention also consists in the features of construction and combination of parts as described in the specification, pointed out in the claims, and illustrated in the accompanying drawings.

In the accompanying drawings, Figure 1 shows a portion of an electric transportation system embodying my invention. Fig. 2 is an enlarged view in elevation of one of the motor-cars, showing the method of suspending the car from the wires. Fig. 3 is an end elevation of the same. Fig. 4 is a diagrammatic view showing the arrangement of wires on a downgrade. Fig. 5 is a diagrammatic view showing the arrangement of wires at a station. Fig. 6 is a view showing same in side elevation.

Again referring to the drawings, 1 represents the supporting-posts for the wires which carry the current and which also form the supports or tracks for the cars. On each post are arranged two brackets 2, and each bracket is provided with two oppositely extending arms 4. The arms on the upper bracket are arranged directly above the arms on the lower bracket. On the arms 4 are arranged wires 5, on which the cars travel and which also constitute the electric circuit. The wires on one side of the posts 55 are for the cars traveling in one direction, and the wires on the other side of the posts

are for the cars traveling in the opposite direction. Each pair of wires is suitably connected with an electric generator. (Not shown.)

The motor car or driver comprises a frame or body portion 15, at each side of which is mounted a standard 16, and the standard at one end of the frame is formed longer than the standard at the opposite end of the frame, the difference between the lengths of the standards depending on the distance between the wires on which the car travels. A cross-bar 17 is pivotally secured at its center to the top of each standard 16, and at each end of each cross-bar 17 is journaled a shaft 18. On one end of each of the shafts 18 is rigidly secured a grooved wheel 19, and on each opposite end thereof is secured a sprocket-wheel 20. The wheels 19 on the standard at one end of the frame 15 are arranged to travel on the upper wire, and the wheels 19 on the standard on the opposite end of the frame 15 are arranged to travel on the lower wires. The front and back ends of the car being thus hung from different wires, the wheels are not so liable to run off of the wires as they would be if the whole car were hung from the same wire. Near each end of the standards 16 is arranged an electric motor 23, of any suitable construction. On the driving-shaft 24 of each motor is secured a gear-wheel 25. A shaft 26 is mounted near the base of each standard 16, and thereon is mounted a gear-wheel 27, which is arranged to mesh with the gear-wheel 25. To the gear-wheel 27 is secured a sprocket-wheel 28. A sprocket-chain 29 operatively connects the sprocket-wheel 28 with the sprocket-wheel 20. One terminal of one motor is electrically connected with one terminal of the other motor by a suitable conductor 30, and one terminal of each motor is electrically connected with the grooved wheels 19 on the adjacent standard 16, by the driving mechanism. The electric current will therefore flow from one wire through the wheels thereon, then through the motors and to the other wire through the wheels thereon.

In Fig. 1 is shown a trailer coupled to the motor which comprises a car-body 40, which is provided with supports 41 at each end, and on the ends of the supports are mounted grooved wheels 42. The wheels at one end of the car-body rest on the upper wire, and the wheels on the other end rest on the lower wire.

In Fig. 4 is shown a method of dispensing with the use of the current when the motor is traveling down a grade. This is accomplished by insulating a section of one of the 5 wires on the downgrade, as at *a*, and then shunting the current around the insulated section by means of a wire *a'*. The car will go down the grade by force of gravity and its momentum and no current will be used in 10 propelling it.

In Fig. 5 is shown a method of constructing a station. Where a station is to be located the going and return wires are curved away from each other, leaving a space for 15 the stations in between. Each station comprises a curved portion 35, preferably formed of cast-iron or a steel rail bent into a curve and a straight portion 36, which may be of wire the same as the main line. Switch-rails 20 37 and 38 are provided which normally form a part of the main circuit, but which may be thrown so as to connect with the station-rails, as shown in dotted lines.

What I claim is—

25 1. In a system of the character indicated, the combination of a series of posts, outgoing and return circuits supported on said posts, each of said circuits comprising two wires, one of which is arranged above the other, a 30 car-frame, a support mounted at each end of said frame, wheels arranged on said supports and adapted to rest on said wires so that the front and back of the car will be supported from different wires, a motor mounted on the 35 said frame, and means for electrically and

mechanically connecting said motor and said wheels.

2. In a system of the character indicated the combination of a series of posts, outgoing and return circuits arranged on said posts, 40 each of said circuits comprising two wires, one of which is arranged above the other, a car-frame, a support arranged on each end of said frame, a cross-head pivotally secured to each support, wheels mounted on said cross- 45 heads, the wheels on one cross-head being arranged to rest on the upper wire and the wheels on the other cross-head being arranged to rest on the lower wire, a motor mounted on said car-frame and means for 50 electrically and mechanically connecting said motor and said wheels.

3. In a system of the character indicated the combination of a series of posts, outgoing and return circuits supported on opposite 55 sides of said posts, each of said circuits comprising two wires one of which is arranged above the other and means for forming a station and for transferring cars from one circuit to the other comprising curved tracks 60 arranged between the outgoing and the return circuits and switches connecting said curved tracks with both of said circuits.

In testimony whereof I sign the foregoing specification in the presence of two witnesses. 65

WILLIAM C. McMURRAY.
